ALBERT G. CARLING, OF NEW YORK, N. Y.

CLOSURE FOR CONTAINERS.

1,179,161.

Specification of Letters Patent. Patented Apr. 11, 1916.

Application filed July 27, 1915. Serial No. 42,146.

To all whom it may concern:

Be it known that I, ALBERT G. CARLING, a citizen of the United States, and a resident of the city of New York, borough of Manhattan, in the county and State of New York, have invented a new and Improved Closure for Containers, of which the following is a full, clear, and exact description.

10 The object of the invention is to provide a new and improved closure for bottles and other containers adapted to contain liquids for use as a mouth wash and other purposes, liquid soap for shampoos or other liquids, 15 and arranged to permit of directing the liquid contents onto a toothbrush or other implement or onto a particular point without scattering or wasting the contents.

In order to accomplish the desired result, 20 use is made of a stopper adapted to fit into the neck of a bottle or similar vessel, a tube extending through the stopper and having a flange overlying the top of the stopper, the upper end of the tube projecting upwardly 25 beyond the said flange and the said upper end of the tube being closed, the side wall of the tube adjacent the closed end being provided with an outlet opening, and a nozzle mounted to turn on the upper portion of the 30 said tube and its flange, the nozzle projecting beyond the closed end of the tube and the nozzle having an integral valve and a recess adjacent the valve, the nozzle when in one position having its valve closing the said 35 outlet opening and the said nozzle when in another position having its recess in register with the said outlet opening.

A practical embodiment of the invention is represented in the accompanying drawings forming a part of this specification, in which similar characters of reference indicate corresponding parts in all the views.

Figure 1 is a sectional side elevation of the nozzle with the parts in closed position; 45 Fig. 2 is a similar view of the same with the parts in open position; Fig. 3 is a sectional plan view of the same on the line 3-3 of Fig. 1; and Fig. 4 is a similar view of the same on the line 4-4 of Fig. 2.

50 The stopper A of cork or other suitable material is of the usual conical shape to snugly fit into the neck of a bottle or similar container filled with a liquid mouth wash, liquid soap, liquid perfume or other liquid. 55 Centrally through the support A extends a tube B open at the bottom and having its

top B' closed and having its side wall a distance below the said top provided with outlet openings B², preferably two in number, located immediately opposite each other. 60 The tube B is also provided with a flange B³ a distance from the openings B² and this flange B³ fits onto the top of the stopper A and its edge B⁴ is curved outwardly and upwardly to fit snugly onto the top of the 65 bottle on which the closure is used.

On the upper portion of the tube B is mounted to turn a nozzle C having a contracted outlet C' a distance above the closed top B' of the tube B. The nozzle C is provided intermediate its ends with a handle C², preferably in the form of a star wheel, to permit the user to conveniently turn the nozzle C on the upper portion of the tube B. The lower end of the nozzle C is provided 70 with a flange C³ overlying the flange B³ of the tube B, and the flange C³ is engaged by a retaining lug B⁵ extending integrally from the flange B³ and overlying the margin of the flange C³ thus holding the nozzle C 75 against upward movement on the upper portion of the tube B. In the lower end of the nozzle C is secured, by brazing or soldering, a short piece of tubing C⁴ which fits snugly onto the tube B, directly above the flange B³, 80 and the said tubing C⁴ is provided with upwardly extending triangularly shaped integral valves C⁵ fitting snugly onto the peripheral face of the upper portion of the tube B to open and close the openings B² on turning the nozzle C. The valves C⁵ are spaced 85 apart to form recesses between them for the passage of the liquid into the nozzle at the time the latter is in the position shown in Fig. 2. When the nozzle C is turned into 90 the position shown in Figs. 1 and 3 then the valves C⁵ close the outlet openings B² thus preventing the liquid in the bottle from passing out of the closure, and when a quarter of a turn is given to the nozzle C to 95 move the latter into the position shown in Figs. 2 and 4 then the valves C⁵ are out of engagement with the outlet openings B² and the latter are now in communication with the interior of the nozzle to allow the 100 liquid to pass through the tube B and by way of the outlet opening B² into the nozzle C and out of the contracted end C' thereof on turning the bottle upside down.

In order to limit the turning motion of the 110 nozzle C as above described, the peripheral edge of the flange C³ is provided with a cut-

out portion C^6 having two shoulders or stops C^7, C^8 adapted to abut against the retaining lug B^5 . It is understood that when the shoulder C^7 is in contact with the lug B^5 (see Fig. 4) then the nozzle is open, and when the shoulder C^8 is in engagement with the lug B^5 (see Fig. 3) then the nozzle C is in closed position relative to the tube B . The cut-out portion C^6 is provided intermediate the shoulders C^7 and C^8 with a recess C^9 adapted to register with the lug B^5 to allow of removing the nozzle C from the tube B or placing it in position thereon, as the case may be. It will be noticed that by the arrangement described the tube B can be readily placed in position on the stopper A and the nozzle C can be readily fitted on the upper portion of the tube B to turn thereon for the purpose above described.

It is understood that when the bottle is tilted and the liquid flows through the outlet opening B^2 , the force of the liquid is broken by contact with the inner surface of the nozzle C so that the liquid is not scattered about but flows unscattered through the contracted end of the nozzle C onto a toothbrush or other implement or onto a particular point on which it is desired to concentrate the liquid.

By reference to Fig. 2, it will be noticed that the openings B^2 are located at the lower ends of the valves C^5 so that any liquid remaining in the nozzle C after the bottle is used and returned to upright position, readily drains back into the bottle by way of the opening B^2 and tube B .

In order to securely hold the tube B in position on the stopper A the lower end of the tube B is provided with a small flange B^6 engaging the under side of the stopper A . Owing to the fact that the stopper is made of cork or similar resilient material it can readily be forced over the flange B^6 onto the tube B , as shown in Figs. 1 and 2.

Having thus described my invention, I claim as new and desire to secure by Letters Patent:

1. A closure, comprising a fixed tube having a closed upper end and having its wall provided with an outlet opening adjacent the said closed end, and a nozzle mounted to turn on the tube and projecting beyond the closed end thereof, the said nozzle having on its inner face an integral valve and a recess, the said nozzle in one position having the said valve closing the said outlet opening and the said valve in another position having the said recess in register with the said outlet opening, and coacting means on the said tube and nozzle to limit the turning motion of the nozzle in either direction.

2. A closure, comprising a stopper, a tube extending through the said stopper and being open at the lower end and closed at the upper end, the said upper end being a dis-

tance beyond the top of the stopper and the side wall of the said upper end having an outlet opening, an integral flange on the said tube intermediate its ends and overlying the top of the said stopper, and a nozzle fitting onto the upper portion of the tube and having a flange fitting on the said tube flange, the interior surface of the said nozzle having a valve and a recess, the said nozzle in one position having the said valve closing the said outlet opening, and the said valve in another position having the said recess in register with the said outlet opening.

3. A closure, comprising a stopper, a tube extending through the said stopper and being open at the lower end and closed at the upper end, the said upper end being a distance beyond the top of the stopper, and the side wall of the said upper end having an outlet opening, an integral flange on the said tube intermediate its ends and overlying the top of the said stopper, and a nozzle fitting onto the upper portion of the tube and having a flange fitting on the said tube flange, the interior surface of the said nozzle having a valve and a recess, the said nozzle in one position having the said valve closing the said outlet opening and the said valve in another position having the said recess in register with the said outlet opening, the said nozzle being provided at its lower end with a flange overlying the flange on the tube, the nozzle flange having a cut-out portion and the tube flange having a retaining lug engaging the said nozzle flange at the cut-out portion to limit the turning movement of the nozzle.

4. A closure, comprising a stopper, a tube extending through the said stopper and being open at the lower end and closed at the upper end, the said upper end being a distance beyond the top of the stopper and the side wall of the said upper end having an outlet opening, an integral flange on the said tube intermediate its ends and overlying the top of the said stopper, and a nozzle fitting onto the upper portion of the tube and having a flange fitting on the said tube flange, the interior surface of the said nozzle having a valve and a recess, the said nozzle in one position having the said valve closing the said outlet opening and the said valve in another position having the said recess in register with the said outlet opening, the said nozzle being provided at its lower end with a flange overlying the flange on the tube, the nozzle flange having a cut-out portion and the tube flange having a retaining lug engaging the said nozzle flange at the cut-out portion to limit the turning movement of the nozzle, the edge of the cut-out portion having a recess adapted to register with the said retaining lug to allow of removing the nozzle from the tube or placing it thereon.

5. A closure provided with a tube closed at the upper end and having outlet openings in its side wall a distance below the upper end, and a nozzle having a contracted outlet and provided in its lower end with a short piece of tubing fixed to the nozzle, the said piece of tubing being mounted to turn on the said tube below the said outlet openings and the said piece of tubing having 10 upwardly extended portions forming valves adapted to close and open the said outlet openings on turning the nozzle.

6. A closure for containers, comprising a stopper, a tube closed at the top and having outlet openings in the side wall a distance below the lower portion of the tube extending through the stopper, a nozzle having a contracted outlet and a short piece of tubing secured in the base end of the nozzle and fitting snugly on the upper end of the said tube, the said piece of tubing having integral upwardly extending valves adapted to open and close the said outlet openings, the said valves forming with the interior 25 surface of the nozzle recesses, and the said

outlet openings being at the lower ends of the said recesses.

7. A closure provided with a tube closed at the upper end, having outlet openings in its side wall a distance below the upper 30 end, a nozzle having a contracted outlet and provided in its lower end with a short piece of tubing fixed to the nozzle, the said piece of tubing being mounted to turn on the said tube below the said outlet openings and the 35 said piece of tubing having upwardly extended portions forming valves adapted to close and open the said outlet openings on turning the nozzle, the said tube and nozzle having coacting flanges, and means for holding the flanges in engagement one with the other.

In testimony whereof I have signed my name to this specification in the presence of two subscribing witnesses.

ALBERT G. CARLING.
